APPARATUS FOR REMOVING BARBS FROM
THE QUILLS OF FEATHERS

August J. Naab, Passaic, N. J.

Application October 15, 1952, Serial No. 314,859

12 Claims. (Cl. 19—4)

1

This invention relates to methods and means for removing the barbs of feathers from the quills and coarser portions of feathers so as to obtain a material which may be used in producing yarns, fabrics, felts and other products.

It has been suggested on numerous occasions heretofore that the barbs of feathers might be used by themselves or with other natural or artificial fibers or hair to produce yarns, fabrics, felts, rug pads and similar products. However, the methods and equipment provided for removing the barbs from the quills have generally been so slow and unsatisfactory in operation as to make the cost of the operation uneconomical. Moreover, only those barbs in the basal or covered portions of feathers are sufficiently soft, fluffy and detached from adjacent barbs to be suitable for use in forming most yarns and fabrics whereas no means has been available heretofore for separating such fluffy barbs from the stiffer, cohering barbs of the vane or exposed portions of feathers. It is for this reason that feathers have never been used in producing yarns, fabrics and fine felts to any significant commercial extent.

In accordance with the present invention these objections to feather stripping equipment of the prior art are overcome and means are provided whereby the fine fluff of feathers may be removed from the quills and coarser barbs and recovered in a form suitable for use in producing yarns, fabrics, high grade felts and other products. The coarser barbs may thereafter be removed from the quills by conventional equipment for use in producing rug pads, coarse felts and other products and the quills and coarse barbs may be treated with acids, alkalies or other chemicals to produce or recover various protein compositions and other constituents thereof.

These results are preferably attained by feeding the feathers to a cutter which is protected by an apertured guard through which air passes in a manner to cause the fluff to stream through the comb into position to be cut from the quills while the coarse and cohering barbs of the vane are shielded from the cutter and retained by the quills for further treatment and use.

One of the objects of the present invention is to provide a novel type of apparatus for selectively removing barbs from feathers.

Another object of the invention is to separate the fluffy barbs of feathers from the cohering barbs of the vane.

A further object of the invention is to provide

2

an improved feather product for use in producing yarns, fabrics, felts and other products.

A specific object of the invention is to provide apparatus for removing barbs from feathers wherein a cutter is shielded by means which permit severing of fluffy barbs from feathers while preventing removal of the cohering barbs of the vane.

These and other objects and features of the invention will appear from the following description thereof wherein reference is made to the accompanying drawing illustrating a preferred type of mechanism which is cited for the purpose of indicating the nature of the invention and without intending to limit the invention thereto.

In the drawing:

Fig. 1 illustrates a typical feather adapted for use in the practice of the present invention;

Fig. 2 is a diagrammatic side elevation of a typical form of equipment embodying the present invention;

Fig. 3 is an enlarged vertical sectional view illustrating a portion of the device shown in Fig. 2; and

Fig. 4 is a front elevation of a portion of the construction shown in Figs. 2 and 3 with parts broken away.

The feather illustrated in Fig. 1 represents a typical breast feather from a chicken and is generally characteristic of all feathers in that it has a quill 2 to which the barbs of the feather are attached. The barbs 4 which make up the vane or exposed portion of the feather include branched interlocking fibers which are so attached to each other as to form a substantially continuous web. However, the basal portion of the feather, which is usually covered, is composed of barbs which are similarly branched but they do not cohere to each other, and therefore, present a light, fluffy, fibrous texture ideally suited for forming yarns, fabrics and soft high grade felts. The barbs 6 of the feathers are therefore more desirable for many uses and are hereinafter referred to as the fluff of the feather.

The equipment illustrated in Figs. 2, 3 and 4 serves to remove the fluff of feathers without removing the barbs or quills with the result that the product obtained is a fine, light, soft material consisting of a multitude of individual and freely separable feather barbs which may be used by themselves or in combination with other natural and synthetic fibers or hair for producing woven or felted materials.

As illustrated in Fig. 1, the feathers are supplied to a hopper 8 from which they move down-

ward to a brush-like feather agitating and feeding device 10 located adjacent an apertured guard 12. In the preferred form of the present invention illustrated, the guard 12 is provided with parallel slots forming a comb with a large number of teeth or spokes which are spaced short distances apart and which are held in predetermined spaced relation by the spacing members 14 as illustrated in Fig. 4. The spacing of the teeth of the guard or comb can be varied by employing spacers 14 of any preferred thickness whereby the teeth 16 of the guard are held in parallel relation and a predetermined distance apart. The brush 10 is arranged so that the bristles thereof project through the guard and between the teeth 16 as the brush rotates. At the rear of the guard a stationary cutter blade 18 is positioned near the lower edge of the teeth 16. A rotary cutter 20 is mounted within a housing 22 on which the guard 12 is supported and the cutter 20 preferably is formed with curving or angularly disposed blades so as to afford a progressive shearing action to sever the portions of the feathers which project through the guard and across the stationary blade 18. A suction device 24 communicates with the chamber 22 in which the cutter 20 is located and the blower, cutter and brush are rotated at suitable speeds by means of a motor 26.

The device further may be provided with an air jet indicated at 28 which extends along the upper edge of the guard adjacent the point where the feathers are moved into engagement with the guard by the rotating brush 10. The air from jet 28 is projected toward the guard 12, whereas the blower 24 creates a powerful suction for drawing air from the jet 28 and from the hopper 8 through the guard in a manner to cause the soft, separated quills of the fluff of each feather to move through the spaces between the teeth 16 of the comb so that they stream through the comb toward the interior of the chamber 22. The bristles of the brush 10 not only agitate and feed the bristles to the guard or comb but they further serve to comb or align the separated barbs of the fluff so that they will extend generally parallel to the teeth of the guard and therefore are drawn through the guard instead of lying transversely across several teeth in a manner which will prevent them from streaming inward into position to be severed from the quills of the feathers. The brush 10 further feeds the feathers downward across the outer face of the guard 12 toward a discharge outlet 30 below the guard 12. Any excess feathers and those having unsheared fluff are engaged by the bristles of the brush and are returned to the hopper so as to be fed again to the guard whereas the feathers from which the fluff has been sheared are more readily disengaged from the brush and are discharged through the outlet 30.

The stationary blade 18 adjacent the lower edge of the guard is positioned to be engaged by the inwardly streaming barbs of the fluff as they move downward across the guard by gravity and under the action of the brush 10. The barbs are then sheared from the quills by the rotating cutter 20 and are carried through the chamber by the blower 24 to a receiving chamber 32. The position of the stationary blade 18 and the thickness and location of the teeth 16 of the comb serve to cause the fluff to be sheared from the quills at a point spaced somewhat from the quills so that the cohering portions of any barbs of the fluff directly adjacent the quill 2 shown at 34 in Fig. 1

are retained by the quill and each individual barb of the fluff is completely separated and disentangled from other barbs. Furthermore, the inwardly streaming air and the combing action of the brush 10 in combination with the teeth 16 insure straightening out of the barbs of the fluff so that they are severed from the quill substantially at the edge of the portion 34 of each feather in a manner to obtain barbs of maximum length which are wholly disentangled from adjacent barbs. The resulting fine, light, fluffy product thus obtained is ideally suited for use in producing yarns, fabrics and high grade felts and further may be combined with other natural and artificial fibers such as wool, silk, cotton, rayon, hair and the like to produce new types of fabrics possessing even greater warmth and softness than natural wool. Moreover, the length of the barbs is such as to impart unusual strength to yarns and fabrics produced from the barbs or in which they are incorporated.

The feathers discharged from the outlet 30 and from which the fluff has been sheared may be subjected to a further stripping, shearing or clipping operation to produce a product composed of the coarser and more entangled barbs of the feathers and the quills or coarse portions of the feathers may be subjected to treatment with acids, alkalies or other chemicals for producing numerous protein products and for the recovery of other constituents of the feathers.

In a typical operation the teeth of the guard in the device to which the feathers are first presented are spaced a very short distance apart so that only the finest and softest barbs of the fluff are sheared from the feathers. The partially sheared feathers which are discharged from the first shearing device then pass to a second device wherein the teeth of the guard are spaced somewhat farther apart whereby the coarser barbs of the fluff are removed from the feathers. The feathers from which the fluff has been largely or entirely sheared then pass to a third device in which a stiff brush rotating at relatively high speed serves to break apart the barbs of the vanes of the feathers and present them for shearing from the quill, after which the quills carrying any unsheared barbs may be passed to a chopper or other device for preparing the feathers for further treatment and use by chemical processes or otherwise.

In this way feather products of varying degrees of fineness and softness may be obtained for use separately in producing different types or grades of products or for use in different operations.

While the blower, cutter and brush may be rotated at various speeds, it is further desirable to maintain a forceful flow of air through the guard to straighten out and draw inward the barbs of the fluff. The brush 10 is preferably rotated at a sufficient speed to insure effective feed of the feathers to the guard and cutter at a rate which insures the maximum production of sheared fluff from the equipment. If the brush 10 is formed with relatively stiff bristles and rotated at high speed, it tends to separate or disentangle many of the barbs of the vanes of the feathers. When the presence of a limited amount of such coarser barbs is not objectionable in the finished product, it may therefore be desirable to rotate the brush 10 at relatively high speed and to form the bristles of the brush of stiff material such as fine flexible wire. The yield of barbs obtained under such conditions is increased, although the texture of

the sheared product obtained is somewhat less fluffy and includes some cohering barbs.

It will further be apparent that the character of the barbs obtained in any operation will also depend upon the type of feathers supplied to the equipment and the spacing of the teeth 16 of the guard 12. When the teeth are relatively far apart, some of the barbs of the vane may project through the comb so as to be sheared along with the fluff.

These and other modifications and changes may be made in the form, construction and arrangement of the elements provided in the practice of the present invention. It should therefore be understood that the particular embodiment of the invention shown in the drawing and described above and the methods of operating the equipment are capable of numerous changes and modifications without departing from the spirit and scope of the invention.

I claim:

1. Apparatus for removing barbs from the quills of feathers comprising a cutter, an apertured guard located adjacent the cutter, means for supplying feathers to said guard on the side thereof opposite to said cutter, and means for causing air to flow past said feathers and through said guard toward the cutter so as to cause barbs on the feathers to stream through the apertures in the guard into position to be engaged by said cutter.

2. Apparatus for removing barbs from the quills of feathers comprising a cutter, a slotted guard located adjacent said cutter, means for supplying feathers to said guard on the side thereof opposite to said cutter, and means for causing air to flow past said feathers and through said guard toward the cutter so as to cause barbs on the feathers to stream through the apertures in the guard into position to be engaged by said cutter.

3. Apparatus for removing barbs from the quills of feathers comprising a cutter, a slotted guard located adjacent said cutter, means for moving feathers across said guard on the side thereof opposite to said cutter and in a direction parallel to the slots in the guard, and means for causing air to flow past said feathers and through said guard toward the cutter so as to cause barbs on the feathers to stream through the apertures in the guard into position to be engaged by said cutter.

4. Apparatus for removing barbs from the quills of feathers comprising a cutter, an apertured guard located adjacent said cutter, a hopper for receiving feathers communicating with the guard on the side thereof opposite to the cutter, a brush located in the hopper adjacent the guard, means for rotating said brush to cause feathers to be moved across the guard, and means for causing air to flow past said feathers and through said guard toward the cutter so as to cause barbs on the feathers to stream through the apertures in the guard into position to be engaged by said cutter.

5. Apparatus for removing barbs from the quills of feathers comprising a cutter, a slotted guard located adjacent said cutter, a hopper for receiving feathers communicating with the guard on the side thereof opposite to the cutter, a brush located in the hopper and rotatable in a direction to cause the bristles of the brush to move lengthwise of the slots in the guard in moving feathers across the guard, and means for causing air to flow past said feathers and guard toward the

cutter so as to cause barbs on the feathers to stream through the apertures in the guard into position to be engaged by said cutter.

6. Apparatus for removing barbs from the quills of feathers comprising a cutter, a slotted guard located adjacent said cutter, a hopper for receiving feathers communicating with the guard on the side thereof opposite to the cutter, a brush located in the hopper and rotatable in a direction to cause the bristles of the brush to move lengthwise of the slots in the guard in moving feathers across the guard, air jet means located adjacent the exterior of the guard for directing air through the guard toward the cutter to cause barbs of the feathers to stream through the guard into position to be engaged by the cutter.

7. Apparatus for removing barbs from the quills of feathers comprising a cutter, a slotted guard located adjacent said cutter, a hopper for receiving feathers communicating with the guard on the side thereof opposite to the cutter, a brush located in the hopper and rotatable in a direction to cause the bristles of the brush to move lengthwise of the slots in the guard in moving feathers across the guard, air jet means located adjacent the exterior of the guard for directing air through the guard toward the cutter to cause barbs of the feathers to stream through the guard into position to be engaged by the cutter, and suction means drawing the cut barbs away from the cutter.

8. Apparatus for removing barbs from the quills of feathers comprising a rotary cutter, a guard located adjacent said cutter and having slots therein extending parallel to the direction of rotation of the cutter, a stationary cutter member located adjacent the ends of the slots in the guard and on the inner side of the guard in position to cooperate with the rotary cutter to shear barbs projecting through the slots in the guard from quills of feathers located on the exterior of the guard, means for supplying feathers to the exterior of the guard, and means for causing air to flow through said guard and past said feathers to cause barbs of the feathers to stream through said slots into position to be severed from the quills by said cutter.

9. Apparatus for removing barbs from the quills of feathers comprising a rotary cutter, a guard located adjacent said cutter and having slots therein extending parallel to the direction of rotation of the cutter, a stationary cutter member located adjacent the ends of the slots in the guard and on the inner side of the guard in position to cooperate with the rotary cutter to shear barbs projecting through the slots in the guard from quills of feathers located on the exterior of the guard, means for supplying feathers to the exterior of the guard, and means for causing air to flow through said guard and past said feathers to cause barbs of the feathers to stream through said slots into position to be severed from the quills by said cutter, and a rotatable brush located on the exterior of the guard and rotatable in a direction to cause the bristles of the brush to travel parallel to the slots in the guard and to project through said slots in an area spaced from the cutter.

10. Apparatus for removing barbs from the quills of feathers comprising a rotary cutter, a guard located adjacent said cutter and having slots therein extending parallel to the direction of rotation of the cutter, a stationary cutter member located adjacent the ends of the slots in the guard and on the inner side of the guard

in position to cooperate with the rotary cutter to shear barbs projecting through the slots in the guard from quills of feathers located on the exterior of the guard, means for supplying feathers to the exterior of the guard, air jet means located adjacent the guard on the exterior thereof directing air through the guard toward the cutter to cause barbs on the feathers to stream through the guard into position to be severed from the quills by the cutter.

11. Apparatus for removing barbs from the quills of feathers comprising a rotary cutter, a guard located adjacent said cutter and having slots therein extending parallel to the direction of rotation of the cutter, a stationary cutter member located adjacent the ends of the slots in the guard and on the inner side of the guard in position to cooperate with the rotary cutter to shear barbs projecting through the slots in the guard from quills of feathers located on the exterior of the guard, means for supplying feathers to the exterior of the guard, and a rotatable brush located on the exterior of the guard and rotatable in a direction to cause the bristles of the brush to travel parallel to the slots in the guard and to project through said slots in an area spaced from the cutter, air jet means located adjacent the guard on the exterior thereof directing air through the guard toward the cutter to cause barbs on the feathers to stream through the guard into position to be severed from the quills by the cutter.

12. Apparatus for removing barbs from the quills of feathers comprising a rotary cutter, a

guard located adjacent said cutter and having slots therein extending parallel to the direction of rotation of the cutter, a stationary cutter member located adjacent the ends of the slots in the guard and on the inner side of the guard in position to cooperate with the rotary cutter to shear barbs projecting through the slots in the guard from quills of feathers located on the exterior of the guard, means for supplying feathers to the exterior of the guard, and a rotatable brush located on the exterior of the guard and rotatable in a direction to cause the bristles of the brush to travel parallel to the slots in the guard and to project through said slots in an area spaced from the cutter, air jet means located adjacent the guard on the exterior thereof directing air through the guard toward the cutter to cause barbs on the feathers to stream through the guard into position to be severed from the quills by the cutter, and suction means located beyond the cutter drawing air through the guard and serving to carry the sheared barbs away from the cutter.
